UNITED STATES PATENT OFFICE

GISBERTO VALLAGUZZA, OF MILAN, ITALY

DESIGN FOR A CASE-BEARER BUCKLE FOR BATHING BELT

Application filed April 2, 1930, Serial No. 35,101, and in Italy March 17, 1930. Term of patent 7 years.

To all whom it may concern:

Be it known that I, GISBERTO VALLAGUZZA, subject of the King of Italy, residing at Milan, Italy, have invented a new, original, and ornamental Design for a Case-Bearer Buckle for Bathing Belt, of which the following is a specification, reference being had to the accompanying drawings, forming part thereof.

I claim:

The ornamental design for a case-bearer buckle for bathing belt substantially as shown.

GISBERTO VALLAGUZZA.
